UNITED STATES PATENT OFFICE.

BENJAMIN WEXLER, OF BROOKLYN, NEW YORK, ASSIGNOR TO THE PEELLE CO., OF NEW YORK, N. Y., A CORPORATION OF NEW YORK.

LATCH FOR ELEVATOR-DOORS.

1,072,064.

Specification of Letters Patent.

Patented Sept. 2, 1913.

Application filed January 16, 1911. Serial No. 602,759.

To all whom it may concern:

Be it known that I, BENJAMIN WEXLER, a subject of the Czar of Russia, and resident of Brooklyn, in the county of Kings and State of New York, have invented certain new and useful Improvements in Latches for Elevator-Doors, of which the following is a specification.

The invention relates to improvements in latches for elevator-doors, with particular reference to manually-opened self-closing fireproof doors leading to an elevator shaft; and the object of the invention is to provide a latch for maintaining a door in open position when the elevator-car is alined therewith, and which when the car is shifted from such position, will remain disengaged therefrom to permit of the automatic closing of the door as a protection against accident or fire.

A further object of the invention is to provide a latch-releasing means including a fusible-link connection adapted to operate in the event of fire to release and close the door when latched in open position.

The invention also includes a recoil device operating in conjunction with the latch to facilitate the closing of the door. And a further object comprehends an arrangement of parts for convenient adjustment and accommodation to irregularities in the construction of the elevator shaft and car supports.

In describing the invention in detail reference is had to the accompanying drawing, forming a part of this specification, and wherein like characters of reference are used to designate like parts throughout the several views, and in which:

Figure 1 is a side elevation of an elevator-doorway, having upper and lower door sections suitably connected together and provided with the improved latch embodied in the present invention; Fig. 2, a transverse section of the doorway, shown in relation to the door sections and latch; Fig. 3, an enlarged ground plan of the latch, with the adjacent parts shown partially in section; Fig. 4, an enlarged side view of a projected latch; and Fig. 5, a similar view of a retracted latch.

Numerals 1 and 2 designate respectively the adjacent portions of the upper and lower sections of a two-part fireproof elevator-

door, to the lower section of which is secured a carrier-bar 3, connected at its opposite ends to the flexible bands or chains 4, which lead over the carrier-wheels 5, and are secured to the upper door section. The wheels are mounted upon guide-rails 6, which are fixed to the wall of the elevator-shaft and provided with interior angles 7 for slidingly receiving the guide-blocks 8, secured to the door-sections, which, as thus mounted, are adapted for vertical movement 65 from and toward each other for opening and closing a doorway 9, leading to the elevator-shaft, the upper door-section being more heavily constructed to have an overbalancing effect upon the lower section to cause a self-closing action of the door when opened.

Within the elevator-shaft is movably supported a car of ordinary construction, indicated by the fragmental portion of an upright 10 and a platform 11, to the latter of which is secured a hanger 12, carrying a cam 13.

Upon one of the guide-rails 6 is fixed an angle frame 14, carrying a pin 15 for pivotally supporting a latch-lever 16, on the upper end of which is fixed a pin 17 for hingedly supporting a latch-member 18. The lower edge of this member is beveled and engages a correspondingly beveled shoulder 19 formed on the latch-lever to serve as a stop to limit the relative movement in one direction about the pin 17, the member being normally retained against the stop by the action of the spring 20, one end of which engages a pin 21, fixed to the latch-member, while the other end is coiled about and fixed to the pin 21a. The latch-member as thus yieldingly supported upon the latch-lever jointly swings therewith about the pin 15, and is normally retained in a retracted position, shown in Fig. 5, by the spring 22, one end of which engages the lower end of the latch-lever while the opposite is coiled about and fixed to the pin 23. The lower end of the latch-lever is also provided with a slot or perforation, through which extends the shank 24 of the shoe 25, which is adjustably retained in position by the set-screw 26, provided in the lever. The movement of the lever is effected by the cam 13, fixed to the car and engaging the shoe, the lateral adjustment of the latter with respect to the lever serving not only to take

up the wear of the parts but as an accommodation for irregularities in the construction of the elevator. Also secured to the angle-frame 14 are a pair of guide-blocks 27, having perforations therein to slidably receive a recoiler-stem 28, provided at its upper end with a contact-head 29 and at a point intermediate the guide-blocks with a thrust-collar 30, which engages the upper end of a spiral compression spring 31, arranged to encircle the stem 28 and bear at its lower end upon the lower guide-block.

The actuation of the recoiler is effected by the manual operation of opening the door, 15 wherein the bottom edge of carrier-bar 3 of the lower door section in its lowermost position engages the contact-head 29 to lower the same and compress the recoil-spring 31, which is retained thus compressed by the engagement of the latch-member 18 with the upper edge of the carrier-bar 3, the downward movement of this bar being positively limited by its engagement with the ledge 32 formed on the angle frame 14. Upon the 20 release of the latch-member 18, the spring 31 serves to upwardly move the carrier-bar and its connected lower door section to facilitate the closing of the door by overcoming its inertia of rest.

As shown in Figs. 2 and 4, the latch is in its outward or projected position as actuated by the cam 13, fixed upon the car, in which position the door, if closed, may be readily opened, during which movement the latch member 18 is inwardly urged about its pivotal support by the bar 3 against the action of the latch-spring 20, which independently projects the latch member upon the complete downward movement of the bar and serves 40 to thus retain the same against the action of the recoil-spring 31. Upon the movement of the car in either direction, the cam 13 is disengaged from the shoe 25, which movement permits of a retraction of the latch-lever and 45 its connected latch member by the spring 22, for the automatic closing of the door. Also to provide, in the event of an adjacent fire, for the closing of the door when openly locked by the elevator-car, a bolt 33, having 50 a head 34, is slidably mounted in guide-lugs 35, fixed upon the angle-frame 14, which latter is also provided with an eye-connection 36 for receiving one end of a tension-spring 37, the opposite end of which 55 is secured to an eye 38, fixed in the projecting terminal 39 of the bolt 33. To the terminal 39 is also fixed an eye 40 for receiving one end of a wire 41, which is led upwardly to an adjacent point within the building 60 where its opposite end is connected to an ordinary fixed fusible-link 42, which normally acts in opposition to the spring 37 to retain the bolt 33 in its upper or clear position with respect to the latch-member 18. In the event of an adjacent fire the fusible

link 42 is parted and the resistance of the wire 41 overcome, permitting the tension of spring 37 to effect a downward movement of bolt 33. The head 34 of this bolt is provided with a beveled working face 43, which 70 engages the projecting end of the latch-pin 21 and urges the latch member inward against the action of the spring 20 to effect the release of carrier-bar 3 and permit the closing of the door.

The several parts comprising the latch being thus operatively associated upon the angle or latch frame 14, it will be obvious that the same may readily be adjusted and secured to the guide-rail or other point adjacent the elevator-car, and, in situations requiring the use of relatively wide doors, latches operating upon both ends of the carrier-bar may be employed.

With the use of the above-described latch 85 it will be clear that upon the opening of the elevator-door the same will remain open only when the car is suitably alined therewith under normal conditions of temperature, and will automatically close under all other 90 conditions if manually released.

What I claim as my invention and desire to secure by Letters Patent, is:

1. The combination with a manually-opened self-closing elevator-door having a carrier-bar secured thereto, of a latch supported adjacent said door and normally held out of engagement with said carrier-bar, a recoiler supported adjacent said latch and adapted to be engaged by said carrier-bar, an elevator-car, a cam fixed to the car for projecting said latch for engagement with the carrier-bar, whereby the door may be held in open position in opposition to the recoiler when the car is alined with respect thereto, and latch-releasing means including a fusible-link connection adapted to operate when the door is latched in open position.

2. The combination with a self-closing vertically slideable elevator-door, of a spring-retracted latch-lever pivotally supported adjacent said door, a yielding latch-member pivotally carried by said latch-lever and adapted to engage and hold the door in open position, a shoe adjustably secured to said latch-lever, an elevator-car, and a cam fixed to the car and adapted to engage said shoe and project the latch-lever for the engagement of the latch-member to hold the door in open position while the car is at rest at 110 that floor of the building and to release said latch and allow the door to close when the car leaves the floor in either direction.

3. The combination with a manually-opened self-closing elevator-door, of a latch-frame fixed adjacent thereto, a latch-lever yieldingly mounted upon said frame, a latch member yieldingly mounted upon said latch-lever and normally held out of engagement with said door, an elevator-car, a cam se- 125

1,072,064.

cured to the car and adapted to project said latch member for engagement with said door, a bolt slidably mounted upon said frame and adapted to retract said latch member independently of said latch-lever, a spring normally disposed to actuate said bolt, a fusible-link secured adjacent said door, and a connection between said link and bolt whereby the latter is held out of

engagement with said latch member in op- 1 position to said spring.

Signed at New York, in the county of New York and State of New York this tenth day of January, A. D. 1911.

BENJAMIN WEXLER.
